UNITED STATES PATENT OFFICE.

AMOS A. WYCKOFF, OF SANTA CRUZ, CALIFORNIA, ASSIGNOR OF ONE-HALF TO
EDWARD L. WILLIAMS, OF SANTA CRUZ, CALIFORNIA.

COIN-CONTROLLED LOCK.

1,110,664.

Specification of Letters Patent. Patented Sept. 15, 1914.

Application filed August 7, 1913. Serial No. 783,519.

To all whom it may concern:

Be it known that I, AMOS A. WYCKOFF, a citizen of the United States, residing at Santa Cruz, in the county of Santa Cruz 5 and State of California, have invented certain new and useful Improvements in Coin-Controlled Locks, of which the following is a specification.

This invention relates in general to locks 10 and has more particular reference to coin-controlled locks adapted for use in connection with storage spaces, lockers, safety-deposit vaults, and the like, which are customarily rented for occupancy for a fixed 15 rate per diem, or other period of time.

Among other desirable objects attained, my present invention is designed to provide a lock which, when unlocked, will prevent withdrawal of a key therefrom and which 20 can be locked only after a coin has been deposited therein, whereupon the key may be withdrawn and retained as a check by the user.

My invention also comprehends the element of time so that, if the goods or articles 25 are left in the locker beyond a predetermined period for which the lock may be set, it will be necessary to deposit one or more additional coins, depending upon the length of 30 time that the lock has been locked, before it can be unlocked again.

Another object is to provide a mechanism 35 which will become operative, only after the maximum period of time for which the lock is designed has expired, to positively prevent unlocking of the lock by the key of the user, with the result that the user must interview the attendant in charge of the lockers and pay the overtime charges before 40 the goods can be released.

Another object is the provision of a lock 45 which will be simple and durable in construction and which cannot be tampered with from the outside so as to impair its efficiency.

Further objects and many of the attendant advantages of this invention will be readily apparent to those skilled in the art as the same is better understood by reference to the following description when considered in connection with the accompanying drawings illustrating one preferred embodiment thereof.

Referring to the drawings—Figure 1 is a front view of a lock embodying my invention; Fig. 2 is a transverse sectional view on the line 2—2 of Fig. 1; Fig. 3 is a longitudinal sectional view on the line 3—3 of Figs. 1 and 4; Fig. 4 is a rear view of the lock showing the locking bolt in unlocked position; Fig. 5 is a similar view showing the position of the parts when the locking bolt is in locked position; Fig. 6 is a sectional view taken on the line 6—6 of Fig. 4; Fig. 7 is a view taken on the line 7—7 of Fig. 4; Fig. 8 is a sectional view taken on the line 8—8 of Fig. 4; Fig. 9 is a detail perspective view of the two-piece slide; and Fig. 10 is a detail view showing one of the cams for withdrawing the coin support from operative position.

On the drawings reference character 11 indicates the lock body or frame provided at its edges with rearwardly projecting flanges 12 and 13 having slots formed therein to support and guide the locking bolt 14. This bolt is provided, as shown in dotted lines in Fig. 4, on its front face with a coin groove 15 which, when the bolt is in unlocked position, is disposed in alinement with the lower end of a coin slot formed by a two-part slide, the parts of which are indicated in Fig. 9 by reference characters 17 and 18, slidably secured to the frame 11 by overlying flanges of rollers 19 mounted on screws 21, or other preferred fastening means. The frame is provided adjacent its top with a pair of coin-receiving apertures 22 and 23 disposed in alinement with the coin slots 16 and 24, respectively, of the two-part slide.

The locking bolt 14 is provided at its upper edge with a recess 25 rounded at one side as indicated at 26, this recess being adapted to receive the downwardly projecting finger 27 of the slide and, when the parts are in unlocked position as shown in Fig. 4, this finger precludes locking movement of the bolt, the finger being held in engagement in this recess by means of a leaf-spring 28 fixed to the frame and pressing against a pin 29 projecting rearwardly from the post 31 of the lower part of the slide. When the parts are in unlocked position, as shown, a bar or plate 32 formed across the front of the coin slot 24 covers the coin-re-

ceiving aperture 23 so that a coin can be deposited in the lock only through the aperture 22. A similar plate or bar 33 over the coin slot 16 serves to close the opening 22 when the locking bolt is in locked position so that the slide is raised to the position shown in Fig. 5. The slide is made in two parts in order that the locking finger may not be lifted out of engagement with the bolt by inserting a knife or other instrument through the coin-receiving apertures 22 or 23 from the outside of the lock. This construction therefore obviates tampering with the lock.

15 A key-cylinder 34 mounted in the casing 35, both of which may be of well known or preferred construction, is supported in the frame 11 beneath the locking bolt and an operating arm 36 fixed to the inner end of the cylinder is equipped at its extremity with a pin 37 projecting into a slot 38 in the locking bolt adjacent to the coin passage 15. The lower end of the finger 27 projects downwardly from the slide into the recess 25 to a point slightly above the center of a coin resting upon the casing 35 in the coin groove of the locking bolt and, when the key-cylinder is turned, through the instrumentality of a key 39 inserted therein, to swing the arm 36 from the position shown in Fig. 4 to that shown in Fig. 5, the coin acting upon the finger raises the slide to release the finger from the recess 25, thereby permitting the bolt to be moved to locked position. When the parts are in this locked position the aperture 22 is closed by the bar 33 and the aperture 23 is opened to permit the insertion of a coin therein which will drop through the coin groove 24 and 40 through the groove 15 in the locking bolt alined therewith into a coin chute beneath the bolt, which will be later described.

Beneath the locking bolt a latch 41 is slidably mounted in suitable guideways 45 formed in a bracket 42 attached to the main frame and this latch is normally urged into engagement with the bolt by a coiled expansion spring 43 interposed between the lower guideway and a collar 44 on the latch. 50 When the bolt is in unlocked position as shown in Fig. 4 the upper end of the latch engages in a shallow notch 45 to yieldingly retain the locking bolt in unlocked position and prevent rattling of the same. When the bolt is in locked position as shown in Fig. 5 the upper end of the latch engages in a notch 46 formed in the lower edge of the locking bolt and prevents movement of the bolt to unlocked position. It will be manifest, however, from an inspection of Fig. 5 that when the bolt is in locked position a slight initial movement toward unlocked position is permitted before the inner wall of the notch 46 abuts against the latch. 60 This initial unlocking movement is utilized

to release the latch by means of release mechanism which will now be described.

A bell-crank lever 47 pivotally mounted at 48 has one arm 49 thereof attached at 51 to the lower end of the latch 41. The other arm 52 of the lever projects upwardly adjacent to one side of the coin chute 53 and, in effect, forms a portion of one side wall of said chute. A second bell-crank lever 54 pivoted at 55 has one arm 56 disposed opposite to the arm 52, the arm 56 also forming a portion of one side wall of the coin chute 53. The other arm 57 of the bell-crank lever 54 is urged into engagement with the lower edge of the locking bolt 14 by means of a leaf-spring 58, or other preferred means. It will be observed that a notch is formed in the lower edge of the locking bolt to provide an inclined or cam surface 59 which permits the bell-crank lever 54 to assume the position shown in Fig. 5 when the bolt is in locked position. Initial unlocking movement of the bolt will rock the bell-crank lever so that the arm 56 through the intermediary of a coin in the chute will actuate the arm 52 and thereby cause the latch 41 to be withdrawn to release the bolt. It will thus be manifest that the lock can be locked through the intermediary of a coin inserted through the aperture 22 and that when the bolt moves to locked position the coin will drop from the groove in the locking bolt into the coin chute and so long as the coin is sustained in position between the arms 52 and 56 of the bell-crank levers 47 and 54, respectively, the lock may be unlocked without depositing any more coins.

As is well known, it is customary in the checking of articles to charge for the length of time that the articles are checked, the usual charge in railway stations, or similar places, being ten cents for each twenty-four hours. When lockers equipped with my invention are used in lieu of the ordinary checking system, it is obviously essential that the storage charges likewise be proportional to the length of time that the articles are stored. I have, therefore, provided mechanism which will preclude unlocking of the lock and the release of the articles stored until coins proportional in number to the time that the articles have been stored are deposited in the lock. With this end in view, the coin chute is provided on its rear face with an elongated longitudinally extending slot; and a head 61, Figs. 4, 5 and 8, pivotally mounted at 62 upon a reciprocal rack-bar 63, is provided with a pin 64 projecting through said slot into the chute in position to support the coins therein. A coiled expansion spring 65, bearing at its lower end against a rack-bar guide 66 and at its upper end against a shoulder 67 on the bar normally sustains the coin support in

the elevated position shown in Figs. 4 and 5 to support a coin between the bell-crank lever arms 52 and 56.

Let us assume that the lock is designed to give the user a twenty-four hour period of service for a coin of predetermined denomination. If the lock should be left in locked position for more than twenty-four hours a second coin should be deposited before the lock can be unlocked and the goods released and an additional coin should be deposited for each subsequent twenty-four hour period that the lock remains in locked position. With this end in view I have provided mechanism for controlling the position of the coin support so that it travels downwardly in the chute substantially the width of one coin during each twenty-four-hour period, with the result that additional coins must be deposited to fill the coin chute to bring the uppermost coin in operative position between the arms 52 and 56 before the lock can be released.

The time-controlled mechanism comprises a driving shaft 68 mounted in suitable bearings 69 on the frame 11, which shaft is continuously driven by any suitable motive power. In the present instance I have shown a beveled gear 71 fixed to the upper end of shaft 68 adapted to mesh with and be driven by a beveled pinion 72 mounted on a shaft 73 connected with any suitable source of power. When a bank of lockers or similar devices are equipped with my invention the shaft 73 will be extended and geared to each driving shaft 68 so that all the driving shafts will be actuated from the main shaft 73. Beneath and in alignment with the driving shaft 68 I have supported in a stub-bearing 74 a driven shaft 75 which receives motion from the driving shaft through suitable clutch mechanism. While the clutch mechanism may be of any preferred construction, I have shown in the present instance a clutch comprising a driven member 76 slidably but non-rotatably connected with the driven shaft 75 by a pin 77 engaged in slots 78 in an enlarged hollow portion 79 of the driven shaft and a driving member 81 slidably but non-rotatably mounted on the driving shaft 68 by means of a pin 82 working in a slot 83 of the driving shaft, the driving member 81 being adapted to engage with the driven member 76. A coiled expansion spring 84 normally holds the driving member of the clutch in the position shown in Fig. 4 and the driven member is moved longitudinally to close and open the clutch through a link 85 pivoted at its lower end to a ring 86 rotatably connected with the driven member 76 and pivoted at its upper end at 87 to the extremity of the bell-crank lever arm 49. When the lock is in unlocked position as shown in Fig. 4, the clutch member 76 will be held out of

engagement with the member 81 by the latch 41 which is at that time engaged in the shallow notch 45 in the bottom of the locking bolt. When the locking bolt is moved to locked position, however, the latch 41, under the influence of the spring 43 is urged into the deeper notch 46, thereby elevating the outer end of the arm 49 to move the clutch member 76 into operative relation with the member 81. The driven shaft 75 is, therefore, continuously driven from the driving shaft 68 so long as the locking bolt 14 remains in locked position. The driven shaft is equipped adjacent its lower end with a worm 88 meshing with and adapted to drive a worm-wheel 89 (Figs. 4 and 6) loosely mounted on a collar 91 carried by a stub-shaft 92. The outer face of the worm-wheel 89 is provided with clutch teeth 93 and a clutch member 94, splined on the collar 91, is provided with similar clutch teeth 95 adapted to engage with the clutch teeth 93 and lock the rotatable collar 91 to the worm-wheel so that they will rotate together. A pinion 96 is fixed to the collar 91 in position to mesh with and drive a gear wheel 97 meshing with the rack-bar 63. The clutch member 94 is controlled by a lever 98 fulcrumed at 99 upon a bracket 101 and carrying at its upper end a roller or follower 102 which is normally urged against the rear face of the locking bolt 14 by a leaf-spring 103. The rear face of the locking bolt is provided with a depression 104 providing an inclined or cam surface 105. When the locking bolt is in unlocked position the roller 102 rests in the depression 104 and the clutch member 94 is disengaged from the worm-wheel 89 as shown in Fig. 6. When, however, the locking bolt is moved to locked position the roller 102 rides up the inclined face 105 thereby swinging the lever 98 to close the clutch and connect the worm-wheel 89 with the pinion 96.

The driving mechanism just described is timed so that the rack-bar 63 will be drawn downwardly to lower the coin supporting pin 64 in the coin chute a distance equal to the width of a coin during each twenty-four hour period. While I have selected twenty-four hours as constituting the period for purpose of illustration, it will be manifest that the mechanism might be designed and timed to move the coin support the width of a coin during a longer or shorter period of time, if desired. It will be manifest that when the coin support has been lowered the width of one coin the lock cannot be unlocked until another coin has been deposited which will be supported, by the coin already in the chute, in operative position between the bell-crank lever arms 52 and 56 so that the latch 41 will be released upon initial unlocking movement of the locking bolt. If the lock is left in locked position for more

70

120

125

130

than two twenty-four hour periods the coin support will have traveled downwardly a distance which will require the deposit of two coins before an operative connection between the lever arms 52 and 56 can be established, and each subsequent twenty-four hour period that the lock remains in locked position will necessitate the deposit of an additional coin. It will be understood that when the lock is in locked position the coin-receiving aperture 22 is closed and the aperture 23 is opened so that the coins required to permit release of the lock are inserted through the coin-receiving aperture 23 and drop downwardly in the coin groove 24 through the groove 15 in the locking bolt and into the coin chute 53.

The mechanism shown in the present instance is designed to provide for four twenty-four hour periods; in other words, the coin support is designed to travel downwardly a distance equal to the width of four coins, but it will be obvious that the length of the coin chute and the rack-bar might be increased to take care of any desired number of periods.

In order that all of the coins in the lock may be deposited in a till, or other accessible position, each time the lock is unlocked, I have provided means for withdrawing the coin-supporting pin 64 from the coin chute each time the locking bolt is moved to unlocked position, thereby permitting the coins in the chute to drop into a till or collection box (not shown) at the bottom of the chute. As previously explained, the head 61 carrying the coin-supporting pin 64 is pivoted at 62 on the upper end of the rack-bar and a leaf-spring 100 normally holds the coin-supporting pin in operative position in the chute. At the rear of the coin chute upon flanges projecting therefrom, I have pivotally mounted at suitable intervals cam-shaped dogs 106 which are normally held in the position shown in Fig. 8 by expansion springs 107 (Fig. 10) pressing against the tails 108 of the dogs. The head 61 is equipped with a pair of laterally projecting wings 109 which are disposed at an inclination, as shown in Fig. 8, and when the head is lowered these wings travel beneath the dogs 106. When, however, the locking bolt is unlocked thereby releasing the clutch 94, as has been previously described, the expansion spring 65 returns the coin support to its upper normal position and, upon the up-stroke of the head, the wings 109 ride over the cam-shaped dogs 106 thereby withdrawing the coin-supporting pin 64 from the chute. After the head has passed the dogs the pin is returned to normal position in the chute by the spring 100 as will be readily understood. It will be manifest that the purpose of the clutch 94 is to break the connection between the gear 97 and the worm 88

so that the rack-bar 63 carrying the coin support can be returned to normal position by the spring 65.

The mechanism is so proportioned and timed that during the first twenty-four hour period the coin utilized to effect movement of the locking bolt to locked position will remain in operative position between the arms 52 and 56 so that the lock can be unlocked without depositing any more coins. 75 When the twenty-four hour period has expired the coin will have traveled downwardly out of operative relation with the arms 52 and 56 and the wings 109 will have passed beneath the first releasing dog 106. 80 If it should be desired to unlock the lock during the second twenty-four hour period another coin is deposited which will be sustained by the first coin in position between the arms 52 and 56 and, when the locking bolt is moved to unlocked position, the coin-supporting pin 64 will be withdrawn from the coin chute upon return movement of the rack-bar and the coins in the chute will be deposited in the till. 90

In order that the single coin in the chute may be released in case the lock is opened during the first twenty-four hour period, I have provided an arm 111 secured to and depending from the locking bolt 14 and provided at its lower end with a cam-shaped head 112 which is adapted to engage with an upward extension 113 of the head 61 likewise provided with a cam-shaped front face adapted to be engaged by the head 112 which, upon unlocking movement of the bolt, swings the head 61 rearwardly to withdraw the coin-supporting pin. The extension 113 is of sufficient length to be engaged by the head 112 at any time that the lock may be unlocked during the first twenty-four hour period. During subsequent periods the pin is withdrawn by the dogs 106, as has been previously explained. 100

It is desirable, in the event that the lock is left in locked position for a longer period of time than is provided for by the length of the coin chute and the stroke of the rack-bar, that the continuously operating drive shaft be disconnected from the mechanism 110 to obviate breakage or injury of the parts. With this end in view I have provided a lever 114 fulcrumed on the frame at 115 and loosely connected at one end to the longitudinally slid able driving member 81 of the clutch and at its other end to a link 116 slid able in suitable guides 117 and provided at its lower end with a toe 118 projecting at the rear of the coin chute into the path of travel of one of the wings 109 on the head 61. When the head approaches the downward limit of its travel the wing 109 engages the toe 118 carrying the link 116 downwardly with it to thereby rock the lever 114 and disengage the clutch member 81 120 125 130

from the member 76, thereby disconnecting the driving-shaft from the driven shaft so that downward travel of the rack-bar 63 is halted. It should be observed that at this time the clutch 94 is closed so that the worm 88 serves to prevent reverse rotation of the gear wheels 96 and 97 and return movement of the rack-bar. The parts, therefore, remain in this position with the coin-support at the lower end of its travel until the coin chute is filled by the deposited coins, the upper coin then serving to establish an operative connection between the arms 52 and 56 to release the latch 41, as has been previously explained. When the locking bolt is returned to unlocked position the clutch 94 is automatically opened permitting the rack-bar to be returned to its upper position by the spring 65, the coin-supporting pin 64 during its upward travel being withdrawn from the coin chute to permit the discharge of the coins therefrom.

Should the lock be left in locked position beyond the length of time provided for by the coin chute this fact should be brought to the attention of the attendant in order that the user may be required to pay the additional charges due before his goods can be released. I have, therefore, provided an auxiliary locking device which, when the rack-bar reaches the end of its downward movement automatically engages the locking bolt and holds the bolt against unlocking movement until the auxiliary locking device has been released by the attendant. To accomplish this purpose I have mounted an auxiliary lock in the form of a slide 119 upon the flange 12 of the frame, the slide being retained in position by bolts or pins 121 engaged in slots 122. The upper end of the slide is provided with a recess 123 so that the top of the slide overlies the locking bolt. A notch 124 is provided in the upper edge of the locking bolt in position to align with the overlying upper end of the slide when the locking bolt is in locked position. An expansion spring 125, interposed between a bracket 126 and the lower end of the slide 119, normally holds the slide in the elevated position shown in Fig. 4. The lower end of the slide is inturned to provide a toe 127 projecting into the path of travel of one of the wings 109 of the head 61, so that when the head approaches the downward limit of its travel the wing engages said toe and moves the slide downwardly against the force of the spring 125 to engage the overlying upper end in the notch 124, thereby preventing unlocking movement of the locking bolt. A lock 128, comprising a spring-pressed bolt 129 is positioned above the upper end of the slide 119 and when said slide is depressed into engagement with the locking bolt the bolt 129 is disposed over the upper end of the slide and precludes disengagement of the

slide from the locking bolt. The attendant in charge of the lockers is provided with a key which fits the lock 128 and this key must be utilized to unlock this lock and release the slide before the locking bolt can be moved to unlocked position. After the attendant has released the auxiliary lock 119 the user deposits the maximum number of coins provided for by the coin chute and opens the lock in the manner previously described. In order that the attendant may know when the head 61 has reached the downward limit of its travel so that he may begin to compute the overtime charge, I have provided a sight opening 130 in the front face of the frame opposite the position that a coin will assume when the head is in lowered position. A similar sight opening 131 may be provided, if desired, opposite the upper position of a coin in the chute. To prevent tampering with the lock or disfiguration of a coin opposite these sight openings, I contemplate covering them with glass, or other transparent material. It will be obvious that, if it should be so desired, an elongated slot might be provided in the frame extending from one end to the other of the coin chute through which the coins might be observed.

For the purpose of preventing twisting or injury to the key in case the lock should for any reason become stuck or fail to operate, I prefer to extend the end of the cylinder 34 outwardly as indicated by reference character 132 (Fig. 2) so that the sides of the key head will be engaged by this extension to take the torsional strain which may be exerted upon the key.

It is believed that my invention and its mode of operation will be fully understood from the foregoing without further description.

While I have referred throughout the specification to coins as an intermediary for locking and unlocking the lock, it will be manifest that slugs, or other suitable articles, might be employed, if desired, and that the lock may be designed for coins or slugs of various sizes and that the timing mechanism may be constructed to provide for time periods of any desired length. It should also be understood that the structural features shown and described are merely illustrative and that the principle of my invention may be embodied in structures differing materially in their mechanical details without departing from the spirit of the invention or sacrificing any of the material advantages thereof.

I claim:

1. In a coin-controlled lock, the combination of a locking bolt, mechanism for operating said bolt, a coin-releasable device for normally preventing locking movement of said bolt, and a coin-releasable device for

normally preventing unlocking movement of said bolt, said devices being arranged to be successively released by a single coin upon initial movement of said bolt in opposite directions respectively.

- 5 2. In a coin-controlled lock, the combination of a locking bolt, means positioned to engage one edge of the bolt for holding said bolt in locked position, means positioned to 10 engage the opposite edge of the bolt for holding said bolt in unlocked position, and mechanism for operating said bolt, said mechanism being adapted, through the intermediary of a coin upon movement in opposite directions, to release said respective holding means and permit operation of said bolt.

20 3. In a coin-controlled lock, the combination of a locking bolt, a device normally holding said bolt against locking movement, a device normally holding said bolt against unlocking movement, means for operating said bolt, said holding devices being arranged to be successively released by a 25 coin upon initial movement of said bolt operating means, and means for withdrawing said coin from operative relation to said device which holds the bolt in locked position, after said bolt has remained in locked position a predetermined period of time.

35 4. In a coin-controlled lock, the combination of a locking bolt, means for operating the same, a latch normally holding said bolt against unlocking movement, means acting through the intermediary of a coin for releasing said latch upon initial unlocking movement of said bolt, and means for controlling the position of a coin in the lock so that said coin is disposed in inoperative relation to said latch releasing means after the lock has been locked a predetermined time.

40 5. In a coin-controlled lock, the combination of a locking bolt, means for operating the same, a device normally holding said bolt against locking movement, said device being adapted to be released through the intermediary of a coin, a latch normally holding said bolt against unlocking movement, means operating through the intermediary of a coin to release said latch upon initial unlocking movement of the bolt, movement of said bolt from unlocked to locked position being adapted to position a deposited coin 55 in coöperative relation with said last mentioned means, and means for permitting said coin to withdraw from coöperative relation with said means after said bolt has remained in locked position a predetermined period of time so that said latch releasing means can be operated only through the intermediary of a subsequently deposited coin.

60 6. In a coin-controlled lock, the combination of a bolt, mechanism for operating said bolt, a single latch normally preventing

movement of the bolt to unlocked position, means actuated by the locking bolt upon initial unlocking movement thereof for releasing said latch through the intermediary of a coin, and time-actuated mechanism for preventing the release of said latch until coins proportional in number to the time that said bolt has remained in locked position have been deposited in the apparatus.

70 7. In a coin-controlled lock, the combination of a locking bolt, means releasable through the intermediary of a coin for holding said bolt in unlocked position, mechanism releasable by a coin normally holding said bolt in locked position, and time-actuated mechanism for insuring the deposit of coins proportional in number to the time that said bolt remains in locked position before said means for holding the bolt in locked position can be released.

75 8. In a coin-controlled lock, the combination of a locking bolt, means for operating said bolt, a latch to normally hold said bolt in locked position, mechanism operable only when a coin is disposed in predetermined position relatively thereto for releasing said latch, and means for insuring the deposit of coins proportional in number to the time that the bolt has remained in locked position before a coin will be disposed in said predetermined position to operate said latch releasing mechanism.

80 9. In a coin-controlled lock, the combination of a locking bolt, means for operating said bolt, mechanism for preventing movement of said bolt from locked to unlocked position, a lever connected to said mechanism, a second lever spaced from said first lever and positioned to be operated by said bolt, and means for holding a coin in position to form a connection between said levers whereby said mechanism is released upon initial unlocking movement of said bolt.

85 10. In a coin-controlled lock, the combination of a locking bolt, means for operating said bolt, a spring-pressed latch for preventing movement of said bolt from locked to unlocked position, a coin chute, a bell-crank lever having one arm connected with said latch and its other arm disposed adjacent to said chute, and a second bell-crank lever having one arm thereof disposed adjacent the opposite side of said chute and its other arm engaged with said bolt, whereby upon initial movement of the bolt toward unlocked position said first-mentioned lever will be operated from said second-mentioned lever through the intermediary of a coin in said chute to release said latch.

90 11. In a coin-controlled lock, the combination of a locking bolt, a latch for holding said bolt in locked position, a coin chute, means for supporting coins in said chute, mechanism operable through the interme-

diary of a coin in said chute to release said latch, and means automatically actuating said coin-supporting means, to vary the position of a coin in said chute while the locking bolt remains in locked position.

12. In a coin-controlled lock, the combination of a locking bolt, a latch adapted to engage therewith, a coin chute, a coin support movable longitudinally of said chute, mechanism for lowering said support when said bolt is in locked position, and means for returning said support to normal position when the bolt is moved to unlocked position.

13. In a coin-controlled lock, the combination of a locking bolt, a latch for engaging said bolt, a coin chute, a coin support therein, mechanism for lowering said support proportionately to the time that said bolt remains in locked position, means for returning said support to normal position when the bolt is moved to unlocked position, and means for withdrawing said support from beneath the coins in the chute upon the return movement of said support.

14. In a coin-controlled lock, the combination of a locking bolt, a latch to hold said bolt in locked position, a coin chute, mechanism operable through a coin in said chute upon initial unlocking, movement of said bolt to release said latch, means for supporting the lowermost coin in said chute at variable heights depending upon the time that said bolt has remained in locked position, and means for withdrawing said support from operative position in the chute to permit the coins in said chute to be delivered therefrom when said locking bolt is moved to unlocked position.

15. In a coin-controlled lock, the combination of a coin chute, a coin support normally disposed in said chute, time-actuated mechanism for moving the support longitudinally of the chute in one direction, means for returning said support in the opposite direction, and mechanism for withdrawing the support from operative position in said chute upon return movement thereof.

16. In a coin-controlled lock, the combination of a locking bolt, a coin chute adapted to contain a plurality of coins, a coin-controlled mechanism for preventing movement of said bolt from locked to unlocked position, a coin support in said chute movable longitudinally thereof, and means for withdrawing said support laterally from said chute upon movement of the locking bolt to unlocked position.

17. In a coin-controlled lock, the combination of a locking bolt, means for operating said bolt, a latch normally holding said bolt in locked position, a coin chute, a coin support in said chute, means for moving said support to vary the position of a coin

in said chute in accordance with the length of time that said locking bolt has remained in locked position, and means operated by said bolt to permit release of the coins from the chute.

18. In a coin-controlled lock the combination of a locking bolt, means for operating said bolt, a coin chute beneath the bolt, means for supporting coins in various positions in said chute, and mechanism operating upon said means to permit a predetermined variation in the position of a coin in said chute during a predetermined time period.

19. In a coin-controlled lock, the combination of a locking bolt, means for operating said bolt, a coin chute, a coin support projecting into said chute, means rendered operable upon movement of said bolt to locked position for lowering said support in said chute, and means rendered operable upon movement of the bolt to unlocked position for withdrawing said support from the chute and returning the support to normal position.

20. In a coin-controlled lock, the combination of a locking bolt, a time-actuated driving shaft, a driven shaft, a clutch interposed between said shafts, a coin chute, a coin support therein, connections between said driven shaft and said coin support, means for closing said clutch upon movement of the locking bolt to locked position whereby to move said coin support longitudinally of the coin chute in one direction, means for opening said clutch upon movement of the locking bolt to unlocked position, and means for returning said coin support to normal position upon opening of said clutch.

21. In a coin-controlled lock, the combination of a locking bolt, means for operating said bolt, a coin chute, means for controlling the position of coins in said chute, a time-controlled driving shaft, mechanism including a clutch for connecting said shaft with said coin-position controlling means, and means operated from said locking bolt for actuating said clutch.

22. In a coin-controlled lock, the combination of a locking bolt, a coin chute, means for controlling the position of coins in said chute, a time-controlled driving shaft, mechanism including a clutch connecting said shaft with said coin-position controlling means, means operated upon movement of said locking bolt to locked position for closing said clutch to move said coin-position controlling means, and mechanism operable after a predetermined period of time for opening said clutch.

23. In a coin-controlled lock, the combination of a driving shaft, a driven shaft, a clutch interposed between said shafts, a coin chute, a coin support therein, operable connections between said driven shaft and said

- coin support, means for closing said clutch to move said coin support in one direction, and means for opening said clutch after a predetermined movement of said coin support has been effected. 5
24. In a coin-controlled lock, the combination of a locking bolt, means for operating said bolt, a driving shaft, a driven shaft, a primary clutch interposed between said shafts, a coin support, connections between said driven shaft and said coin support including a secondary clutch, a coin-controlled mechanism for operating said primary clutch, and means actuated by said locking bolt for operating said secondary clutch. 10
25. In a coin-controlled lock, the combination of a locking bolt, means for normally holding said bolt in unlocked position, said means being rendered inoperative through the intermediary of a coin, means for holding said bolt in locked position, mechanism subsequently operable through the intermediary of the same coin for releasing said last-mentioned means, and means for automatically positioning said coin in inoperative relation to said mechanism after a predetermined period of time. 15
26. In a coin-controlled lock, the combination of a locking bolt, a coin-released latch for locking said bolt in unlocked position, a coin-released device for locking said bolt in locked position, and an automatically operated coin-positioning device for precluding the release of said coin-released device except upon deposit of a predetermined number of coins, after the first coin has been carried to inoperative position by said coin positioning device. 20
27. In a coin-controlled lock, the combination of a locking bolt, means for holding said bolt in locked position, coin-controlled mechanism for releasing said means, and a time-controlled device releasable independently from said coin-controlled mechanism for locking said bolt against unlocking movement after the bolt has remained in locked position a predetermined period of time. 25
28. In a coin-controlled lock, the combination of a locking bolt, means for operating said bolt, coin-controlled means for holding said bolt in locked position, coin positioning means for determining the number of coins to be deposited before said coin-controlled means can be released, and an auxiliary latch adapted to be moved by said positioning means into locking engagement with said bolt when said coin positioning means approaches the limit of its travel in one direction to hold said bolt against unlocking movement. 30
29. In a coin-controlled lock, the combination of a locking bolt, mechanism for so controlling the position of coins in the lock 35 that said bolt cannot be unlocked unless coins proportional in number to the time the bolt has remained in locked position are disposed in the lock, and means movable by said coin-controlling mechanism into locking engagement with said bolt to prevent unlocking of the bolt after the period provided for by the coin-controlling mechanism has expired. 70
30. In a coin-controlled lock, the combination of a locking bolt, means for operating said bolt, a coin chute, a coin support movable therein, time-controlled mechanism for moving said support longitudinally of the chute, and means operated when said support reaches a predetermined position in its travel for locking said locking bolt against unlocking movement. 75
31. In a coin-controlled lock, the combination of a locking bolt, means for operating said bolt, a coin chute, a coin support, means for actuating said support, a lock adapted to engage said locking bolt, means for normally retaining said lock in inoperative position, means in the path of movement of said coin support whereby said lock is moved into operative position by the support to prevent unlocking movement of the locking bolt, and key-releasable means for automatically retaining said lock in locked relation with the locking bolt. 80
32. In a coin-controlled lock, the combination of a frame, a locking bolt slidably mounted therein, means for operating said bolt, a slide providing a plurality of coin chutes disposed in coöperative relation 85 with corresponding coin-receiving apertures in said frame, and means carried on said slide whereby one of said apertures is closed when another is opened. 90
33. In a coin-controlled lock, the combination of a frame provided with a pair of coin-receiving apertures, a locking bolt slidably mounted in said frame, means for operating said bolt, a slide adapted to engage with said bolt and prevent locking movement of the bolt except upon the introduction of a coin into one of said apertures, and closures carried by the slide adapted to close one of said apertures when the other is opened. 95
34. In a coin-controlled lock, the combination of a frame provided with a pair of coin-receiving apertures, a grooved slide mounted on said frame providing a pair of coin chutes in alignment with said apertures, a locking bolt, means for operating said bolt, means carried by the slide to engage said bolt and prevent locking movement thereof, and a spring for urging said slide toward the bolt. 100
35. In a coin-controlled lock the combination of a frame provided with an aperture, a locking bolt, means for operating said bolt, and a slide providing a coin chute from said aperture to said bolt and 105

having a projection adapted to engage with said bolt to prevent locking movement thereof except upon the insertion of a coin in said aperture, said slide being made in 5 two parts to permit one part to be raised without withdrawing the other part from engagement with said locking bolt.

36. In a coin-controlled lock, the combination of a frame, a locking bolt slidable 10 therein, a slide adapted to engage said bolt and prevent locking movement thereof, said slide providing a plurality of coin chutes, and means engaging the lower portion of said slide to urge the same into engagement with said locking bolt, the upper portion of the slide being movable relatively to the lower portion to preclude release of the slide from the bolt by an instrument engaged with the upper portion 15 of said slide.

37. In a coin-controlled lock, the combination of a locking bolt, coin-releasable means for holding said bolt in locked 20

position, means for maintaining a coin in operative relation to said coin-releasable 25 means for a predetermined period of time after said bolt has been moved to locked position, and means for controlling said last mentioned means to permit said coin to assume an inoperative relation to said coin- 30 releasable means at the termination of said time period.

38. In a coin-controlled lock, the combination of a locking bolt, coin-releasable 35 means for holding said bolt in locked position, coin-supporting means for supporting a coin in various positions in said lock, and mechanism for automatically operating said last mentioned means to permit a predetermined movement of a coin during a 40 predetermined period of time.
